UNITED STATES PATENT OFFICE

161,714

TABLE WITH ROTATING TOP

Charles B. Shapiro, La Porte, Ind., assignor to
Universal Woodcrafters, Inc., La Porte, Ind., a
corporation of Illinois

Application August 10, 1950, Serial No. 11,716

Term of patent 14 years

(CL. D33—14)

To all whom it may concern:

Be it known that I, Charles B. Shapiro, a citizen of the United States, residing at La Porte, in the county of La Porte and State of Indiana, have invented a new, original, and ornamental Design for a Table with Rotating Top, of which the following is a specification, reference being had to the accompanying drawing, forming part thereof.

Figure 1 is a perspective view of a table with rotating top, showing my new design; and

Figure 2 is another perspective view of the same as it appears when the table top has been rotated from its normal position.

I claim:

The ornamental design for a table with rotating top, as shown.

CHARLES B. SHAPIRO.
